Primary Examiner — Barbara Fox(74) *Attorney, Agent, or Firm* — Cantor Colburn LLP(57) **CLAIM**

I claim, the ornamental design for a tablet PC, as shown and described.

DESCRIPTION

FIG. 1 is a front perspective view of a tablet PC showing our new design;

FIG. 2 is a front elevation view of thereof;

FIG. 3 is a rear elevation view of thereof;

FIG. 4 is a side elevation view of thereof;

FIG. 5 is another side elevation view of thereof;

FIG. 6 is a top plan view of thereof;

FIG. 7 is a bottom plan view of thereof; and,

FIG. 8 is a rear perspective view of thereof.

The oblique shade lines in the Figures show transparency and not surface ornamentation.

The broken lines illustrating portions of the tablet PC are for environmental purpose only and form no part of the claimed design.
